UNITED STATES PATENT OFFICE.

GEORGE TAVRA, OF EUREKA, CALIFORNIA.

COMBINATION-PADLOCK.

1,265,136.

Specification of Letters Patent.

Patented May 7, 1918.

Application filed July 26, 1917. Serial No. 182,991.

To all whom it may concern:

Be it known that I, GEORGE TAVRA, a citizen of the United States, residing at Eureka, in the county of Humboldt and State of California, have invented certain new and useful Improvements in Combination-Padlocks; and I do hereby declare the following to be a full, clear, and exact description of the invention, such as will enable others skilled in the art to which it appertains to make and use the same.

The invention relates to a combination pad lock.

The object of the present invention is to provide a simple, practical and efficient permutation or combination padlock of strong, durable and inexpensive construction adapted to be easily operated by any one understanding the combination and equipped with a relatively large number of rotary rings having notches adapted to be brought into line and coöperating with lugs of an arm so that it is necessary to arrange all of the recesses in alinement simultaneously in order to effect an opening of the lock.

With these and other objects in view, the invention consists in the construction and novel combination of parts hereinafter fully described, illustrated in the accompanying drawing and pointed out in the claims hereto appended; it being understood that various changes in the form, proportion, size and minor details of construction, within the scope of the claims, may be resorted to without departing from the spirit or sacrificing any of the advantages of the invention.

In the drawing:

Figure 1 is a perspective view of a combination padlock constructed in accordance with this invention.

Fig. 2 is a longitudinal sectional view of the same, the relatively movable shackle section being unlocked.

Fig. 3 is a transverse sectional view of the padlock.

Fig. 4 is a detail perspective view of one of the rotary rings.

Like numerals of reference designate corresponding parts in the several figures of the drawing.

In the accompanying drawing, in which is illustrated the preferred embodiment of the invention, the combination padlock comprises in its construction a shackle composed of fixed and relatively movable sections 1 and 2, the relatively fixed section 1 being se-

cured to one end of a spindle 3 which has its other end 4 threaded for the reception of the relatively movable shackle section 2. The relatively movable shackle section 2 is provided with a threaded opening 5 for the threaded end 4 of the spindle, and it is adapted to be rotated to arrange it in alinement with the relatively fixed shackle section, as illustrated in Fig. 1, and also to swing it away from said position as shown in dotted lines in Fig. 1. The threaded connection between the section 2 and the spindle provides a pivotal or swinging movement for the said section 2 and the threaded opening 5 preferably extends inwardly from the inner face of the section 2 and terminates short of the outer face thereof. The shackle sections are preferably provided with enlarged circular ends 6 and 7 and are reduced beyond the said ends.

The end 6 is provided with a slot 8 which registers with a longitudinal groove 9 in the bottom portion of the spindle to receive an inner arm 10 of a locking member 11 having an outer arm 12 and conforming to the configuration of the adjacent shackle section 1. The outer arm 12 extends through an opening 13 in the section 1 and is adapted to project into an opening 14 in the section 2 when the said opening 14 is arranged in alinement with the opening 13. When the outer arm is engaged in the opening 14, the section 2 is locked against relative rotary movement, and when the arm 12 is withdrawn from the opening 14 the arm 2 is adapted to be rotated on the end of the spindle and it may be screwed on or off the same. A partial rotation of the section 2 or the spindle will carry the same into and out of register with the section and will open and close the padlock.

The inner arm 10 is provided with recesses 15 forming intervening lugs 16 and adapted to receive flanges 16^a of rings 17 provided with notches 18. The rings are mounted for rotary movement on the spindle and are provided with letters or other characters and they are capable of rotary movement to aline the notches 18 to permit the intervening lugs formed by the recesses 15 to pass through the notches of the flanges 16^a. When one or more of the flanges are out of alinement the locking member will be held against movement and as the recesses 15 form a plurality of lugs, each co-operating with one of the rings, it will be

impossible for anyone to ascertain the position of the recesses by the pressure of the locking member on the same and it will not be possible to operate the rings successively without a knowledge of the recesses and move the locking member outwardly by a step by step movement. While letters are shown to indicate the position of the rings, numbers may of course be used.

10 The spindle is provided with a longitudinal slot 19 and the inner arm of the locking member carries a pin 20 operating in the slot for limiting the inward and outward movement of the said locking member to prevent the arm from being entirely withdrawn from the opening of the relatively fixed shackle section. A washer 21 is shown arranged between the ends of the pivoted shackle section 2 so that the turning of the movable section of the shackle will not change the position of the rings.

What is claim is:

1. A combination padlock of the class described including a shackle divided at the outer portion and composed of relatively fixed and movable sections, a spindle fixed to one of the sections and forming a pivot for the other section, means for holding the pivoted section against sliding movement on the spindle, a locking member located at the relatively fixed section and conforming to the configuration of and fitting against the same and extending to the outer end thereof, said locking member being provided with an arm of a length to extend beyond the fixed section and engage the relatively movable section for holding the same against movement, said locking member being also slideable outwardly to release the relatively movable shackle, and means for locking the said locking member against such outward sliding movement.

2. A combination padlock of the class described including a shackle divided at the outer portion and composed of relatively fixed and movable sections, a spindle secured to one of the sections and forming a pivot for the other section, means for holding the pivoted section against sliding movement on the spindle, a locking member fitting against the relatively fixed section and provided with inner and outer arms, the inner arm slideable inwardly and outwardly along the spindle and carrying the locking member and the outer arm being carried into

and out of engagement with the relatively movable shackle section by the sliding movement of the inner arm, and a plurality of rings mounted on the spindle and having means for engaging the inner arm of the locking member.

3. A combination padlock of the class described including a shackle divided at the outer portion and composed of relatively fixed and movable sections, a spindle secured to one of the sections and forming a pivot for the other section, means for holding the pivoted section against sliding movement on the spindle, a locking member fitting against the relatively fixed section and provided with inner and outer arms, the inner arm slideable inwardly and outwardly along the spindle and carrying the locking member and the outer arm being carried into and out of engagement with the relatively movable shackle section by the sliding movement of the inner arm, said inner arm being provided at intervals with recesses forming intervening lugs, and a plurality of rotary rings mounted on the spindle and provided with flanges operating in the recesses and having notches for the passage of the lugs.

4. A combination padlock of the class described including a shackle composed of relatively fixed and movable sections, the relatively fixed section being provided with an opening, a spindle fixed to the relatively fixed section and having a longitudinal groove extending inwardly from the said opening, said spindle being also provided with a longitudinal slot, a locking member provided with means for engaging the relatively movable shackle section and having an arm slideable in the groove and passing through the opening of the relatively fixed section, said arm being provided at intervals with lugs, rotary rings having flanges operating between the lugs and provided with notches for the passage of the lugs, said rings being mounted on the spindle, and a pin carried by the said arm and operating in the slot for limiting the movement of the locking member.

In testimony whereof I affix my signature in presence of two witnesses.

GEORGE TAVRA.
